UNITED STATES PATENT OFFICE.

CHARLES P. FAY, OF SPRINGFIELD, MASSACHUSETTS.

PLIERS.

Application filed April 5, 1926. Serial No. 99,852.

This invention relates to improvements in hand tools of the plier type and, particularly, to tools of this class wherein a powerful leverage is desired to enable the jaws to be forced together under great pressure for the cutting or other function.

The invention is shown as embodied in cutting pliers but the improvements, obviously, are adapted to other tools of a generally analogous nature, whether the jaws are used for cutting or other purposes.

An object of the invention is to provide a generally improved tool of the general class described, embodying provisions for compound leverage to move the jaws together and stabilizing connections between the jaw-carrying levers and the fulcrum of the handles or operating levers.

Another object of the invention is to provide, in a tool of the class described, working levers made up of pairs of spaced plates and carrying the jaws of the tool, together with a common fulcrum bar which is received between the pairs of plates and to which these pairs of plates are separately pivoted at laterally spaced points, characterized in that the pairs of plates are tied together by the jaws and the fulcrum bar, and in that the plates are engaged with the fulcrum bar over a broad area to afford a rigid and well braced composite structure.

Another object of the invention is to provide, in a tool of the class described, improved stabilizing means, located and mounted in an improved manner.

A further object of the invention is to provide, in a tool of the class described, an improved construction and mounting of the jaws, in a manner enabling convenient adjustment and in a manner well calculated to resist the shocks imposed in operation.

Other objects and advantages will appear in the following description and will be pointed out in the appended claims.

The invention will be disclosed with reference to the illustrative embodiment of it shown in the accompanying drawings, in which:

Fig. 1 is a front elevational view of cutting pliers embodying the invention;

Fig. 2 is a side elevational view thereof;

Fig. 3 is an enlarged fragmentary sectional view taken on the line 3-3 of Fig. 2;

Figs. 4 and 5 are enlarged fragmentary sectional views taken on the lines 4-4 and 5-5, respectively, of Fig. 1; and

Figs. 6 and 7 are fragmentary front and side elevational views of one of the operating levers or handles.

Referring to these drawings; the tool comprises a pair of operating levers 10, the major portion of which constitute handles, and these levers are pivotally connected together by a common pivot 11 and are also pivotally connected at 12 to the lower ends of a pair of working levers 13. The latter are separately pivoted at 14 at laterally spaced points to a common fulcrum bar 15. The working levers 13 carry jaws 16 of any suitable type, herein shown as cutters.

A novel feature of the present invention consists in the particular construction of the working levers 13. Each of these levers comprises a pair of relatively thin plates 17 and the plates of each pair are disposed on opposite sides of the fulcrum bar 15 and in contiguous relation therewith. The fulcrum bar 15 is relatively wide and it extends from the outer edges of one pair of plates 17 completely across said plates, across the intervening space between the pairs of plates, and completely across the other pair of plates 17, terminating at their outer edges. There is, thus, a relatively large and extensive area of contact between the plates and bar, which assures stiffness and rigidity to the tool, notwithstanding that the working levers are made up of relatively thin plates.

Each lever 10 is shouldered down adjacent the pivotal connection 11 to form a substantially circular ear 18 of a thickness equal to that of the fulcrum bar. The lower ends of plates 11 are substantially semi-circular and fit in the recesses formed by the shouldering down of lever 10, being disposed on opposite sides of ear 18. The combined thickness of a pair of plates 17 and the intervening fulcrum bar 15 is approximately equal to the thickness of lever 10, as will be seen from Fig. 2.

The levers 10 are connected by a special pivotal connection, which, while not in itself new, lends itself admirably to one of the purposes of this invention, which is to secure a connection of one of the stabilizing members to the pivot 11 at a point centrally between its ends. It is desired to secure a thin, compact and neat appearing joint and at the same time not to unduly weaken this joint by the presence of the stabilizing member, which is shown at 19 as a small cylindrical rod upstanding from the pivot 11 and

fixed thereto at a point centrally between its ends. Each lever is formed with a recess 20, extending across the entire width of the lever. The surface of this recess is a portion of a cylindrical surface and is adapted to fit the pivot 11 and cover a certain portion of its periphery (somewhat less than 180 degrees). The two surfaces 20 abut the pivot pin 11 on opposite sides thereof and, in the normal position of the levers 10, shoulders 21 thereon abut above the pivot pin 11 and limit the extent of outward spreading movement of levers 10 and also, of course, the outward spreading movement of the working levers 13. The shoulders 22 below pivot pin 11 are not intended to abut under any normal conditions,—other means to be later described, being provided for the purpose of limiting the movement of the levers 10 and 13 in the other direction.

The levers 10 are recessed centrally through their shoulders 21, as shown at 23, for the purpose of providing clearance for the stabilizing member 19 at all times. Except for this recess 23, which is made as small as possible, each lever has a full bearing contact with pin 11. The bearing is as wide as the lever and its arcuate extent is as great as possible. If the levers were connected by a half joint, the arcuate extent of the bearing would be increased but at the sacrifice of its longitudinal extent which is far more important because, during the cutting operation (when all the work is being done), the two levers press against the pivot with the surfaces 20. If the bearing were extended to encompass the side of the pivot opposite from surface 20, this extended portion would be idle during the cutting operation. With the present arrangement the maximum bearing area during the working operation is secured (for a given width of lever and a given diameter of the pivot) and yet the construction allows the stabilizing member 19 to be connected to the pivot pin centrally between its ends with hardly any substantial sacrifice of bearing surface.

In order to hold the levers from displacement on the pivot pin 11, circular heads 24 are provided, which are mounted one on each end of the pin and held in place by upsetting the ends of the pin as best shown in Fig. 5 the heads 24 have inturned marginal flanges 25, which fit into pairs of arcuate grooves 26 (Figs. 6 and 7) formed in the outer faces of the levers 10. Considering the front face of the two levers 10, the groove 26 formed in each is concentric with the pivot pin and the two grooves cooperate to form portions of a circular track-way to receive the flange 25 on a head 24. The engagement of these flanges 25 in grooves 26 holds the levers 10 from endwise and lateral displacement relatively to the pivot. This engagement is adequate for the purpose

because there is at no time any heavy strain imposed upon the parts tending to displace them on or from the pivot pin. At the same time, the construction presents an exceptionally neat and finished appearance and the outer faces of heads 24 do not project beyond the outer faces of plates 17.

The stabilizing member 19, which projects toward fulcrum bar 15, is slidably engaged with a second stabilizing member 27, which is fixed to the bottom face of the fulcrum bar and extends toward pivot pin 11. As shown, member 27 is a cylindrical piece bored out to slidably receive member 19. Loosely mounted on the latter is a short cylindrical member 28 having a flange 29 which functions as a seat for a spring 30. The latter encompasses the telescopically engaged members 19 and 27 and acts between flange 29 and fulcrum bar 15 to hold the operating and working levers in spread apart relation. The lower face of member 29 overlaps a portion of each lever 10 and consequently spring 30 acts to force these portions of levers 10 downwardly until the described shoulders 21 abut. The upper end face of member 28 is adapted to engage the lower end of member 27 as a positive and accurate stop to limit the inward movement of the working levers and prevent the cutters 16 from being damaged.

The function of the stabilizing members 19 and 27 is well understood. They insure, by their action, that a common center line drawn through the centers of pivots 14 will at all times lie at exactly right angles to a line drawn from a point equidistant between the lower ends of the levers 10 and their common fulcrum point 11. Stabilizing members of various types have been used before to accomplish the same function but they have been applied outside the working levers, rather than inside and between the two parts of the same as here shown. Also, they have been connected to the ends of the pivot, corresponding to 11, rather than centrally with respect to the same. By the present construction the stabilizing members and the return spring are kept out of the way and so located that one cannot possibly pinch the fingers between the coacting stops 27 and 28 or have parts of the flesh caught and pinched between convolutions of the spring 30. Moreover, a much neater and more attractive article results.

The cutters 16 are carried one by each working lever 13. Each cutter overlies the upper edge of each plate 17 and has depending flanges 32, which lie one outside each plate and hold the plates against outward spreading, thereby cooperating with the fulcrum bar and the connections 12 with ears 18 to stiffen the working levers and make them extraordinarily rigid. Each plate 17 has a groove 33 formed in its inner face parallel with the edge engaged by cut-

ter 16. The two grooves 33 in each pair of plates 17 afford a slideway to receive the side flanges 34 of a slide 35, which slidably fits between each pair of plates and extends 5 upwardly toward, but not quite to, the lower face of cutter 16. A stud 36 fixed in slide 35 projects through a hole in cutter 16 and the cutter is held to the slide by a screw 37 the head of which is countersunk into the cutter 10 16 and the shank of which is threaded into the slide 35. By tightening the screw 37, the slide is drawn up to cause its flanges 34 to tightly press against the upper edges of grooves 33 and at the same time the cutter 15 16 is drawn tightly down against the upper edges of plates 17. Each plate 17, on its inner surface and above groove 33, is provided with a portion 38 of a screw 20 thread. The two portions 38 on the inner walls of a mating pair of plates 17, are adapted to receive a set screw 39 of as large a diameter as is compatible with the room available for the purpose. The set screws 39 not only serve as a convenient means for 25 adjusting the cutters, when screws 37 are loosened, but they also act as solid abutments to take the shock of the cutting operation and relieve the slides 35 and screws 37 from much of the strain to which they would 30 otherwise be subjected.

The fulcrum bar 15 has still another useful purpose. As shown in Fig. 4, the central portion of this bar, which underlies 16, is grooved on opposite sides, as at 40. These 35 two grooves 40 start at points in the side faces of the bar a little more than half way up and converge upwardly until they meet in a thin line of intersection near the upper edge of the bar. The central cross sectional shape of the bar at its upper portion is therefore a wedge. This wedge-like part 40 functions as a deflector calculated to deflect a wire, when inserted between the cutters 16, either to one side or the other in the event that the wire is inserted so far as to 45 strike the bar 15. If the end of the wire touched the top edge of bar 15 and this edge were flat, then when the wire was cut it would tend to throw the cutters 16 upwardly. As the cutters 16 move together 50 to cut the wire, their cutting edges have a downward movement toward bar 15. Consequently, if the end of the wire abuts this bar before it is cut, the bar resists further 55 downward movement of the wire during the cutting operation and there will be an upward force exerted on the cutting edges, which is undesirable in any event and which is liable, under certain conditions, to damage 60 the cutters. Also, the grooves 40, in conjunction with the spaces between the plates of one pair and those of another, permit a 65 wire passed in a fairly straight course therebetween, whereby the wire may be cut at or near the centers of the cutters rather

than near their ends as with former tools of this type.

The invention affords a tool of the class described which is well adapted for practical manufacture. It is especially adapted 70 for quantity production at low unit cost. The working levers are made up of plates and all the plates are exact counterparts. The levers 10 are likewise exactly alike and adapted for manufacture by drop forging 75 or die casting. The remaining parts are simple and easily produced and as readily assembled. Aside from the manufacturing advantages, a tool is provided which makes a real appeal on account of its attractive 80 appearance and the user gets a really good and serviceable tool as well. The working levers and jaws are extremely rigid and strong on account of their composite construction and the adequate manner in which the component parts cooperate to afford a 85 thoroughly braced structure, well calculated to resist the strains of severe service to which a tool of this character is oftentimes subjected.

The invention has been disclosed herein, in an embodiment at present preferred, for 90 illustrative purposes but the scope of the invention is defined by the appended claims 95 rather than by the foregoing description.

What I claim is:

1. In a tool of the class described, a pair of operating levers pivotally connected to turn upon a common fulcrum, a pivot pin 100 forming said fulcrum, a pair of spaced plates pivotally connected to each operating lever and disposed on opposite sides of the same, a fulcrum bar disposed between said pairs of plates and extending across from the plates of one pair to those of the other with its side faces contiguous with the inner faces of said plates, each pair of plates being separately pivoted to said bar at laterally spaced points intermediate the ends of the plates, slidably engaged stabilizing members disposed in the space between said pairs of plates and between said bar and pivot and fixed one to said bar and one to said pivot, and a jaw carried by each pair of 105 plates.

2. In a tool of the class described, a pair of operating levers pivotally connected to turn upon a common fulcrum, a pivot pin forming said fulcrum, a pair of spaced plates pivotally connected to each operating lever and disposed on opposite sides of the same, a fulcrum bar disposed between said pairs of plates and extending across from the plates of one pair to those of the other with its side faces contiguous with the inner faces of said plates, each pair of plates being separately pivoted to said bar at laterally spaced points intermediate the ends of the plates, slidably engaged stabilizing members disposed in the space between said pairs of plates and be- 110 115 120 125 130

tween said bar and pivot and, fixed one to said bar and one to said pivot, a spring encompassing said members and acting between said bar and operating levers with a tendency to spread the latter apart, and a jaw carried by each pair of plates.

3. In a tool of the class described, a pair of operating levers pivotally connected to turn upon a common fulcrum, a pivot pin forming 10 said fulcrum, a pair of spaced plates pivotally connected to each operating lever and disposed on opposite sides of the same, a fulcrum bar disposed between said pairs of plates and extending across from the plates 15 of one pair to those of the other with its side faces contiguous with the inner faces of said plates, each pair of plates being separately pivoted to said bar at laterally spaced points intermediate the ends of the plates, 20 telescopically engaged stabilizing members one fixed to said pivot centrally between its ends and one fixed to said fulcrum bar, a stop mounted on one of said members and adapted to engage the other to limit the 25 movement of said pairs of plates toward each other when the operating levers are pressed together, and a jaw carried by each pair of plates.

4. In a tool of the class described, a pair 30 of operating levers pivotally connected to turn upon a common fulcrum, a pivot pin forming said fulcrum, a pair of spaced plates pivotally connected to each operating lever and disposed on opposite sides of the 35 same, a fulcrum bar disposed between said pairs of plates and extending across from the plates of one pair to those of the other with its side faces contiguous with the inner faces of said plates, each pair of plates being 40 separately pivoted to said bar at laterally spaced points intermediate the ends of the plates, telescopically engaged stabilizing members, one fixed to said pivot centrally between its ends and one fixed to said fulcrum bar, a stop mounted on one of said members and adapted to engage the other to limit the 45 movement of said pairs of plates toward each other when the operating levers are pressed together, said stop having a spring seat, a spring coiled around said telescopically engaged members and acting between said seat and bar to normally maintain the operating levers in spread apart 50 relation, and a jaw carried by each pair of plates.

5. In a tool of the class described, a pair of operating levers pivotally connected to turn upon a common fulcrum, a pivot pin forming said fulcrum, a pair of working levers pivotally connected to said operating levers, each of said working levers having an opening bounded by spaced parallel walls, a fulcrum bar having its ends disposed in said openings and slidably engaged with said walls and spanning the space between 60 said working levers, said working levers being separately pivoted at points intermediate their ends to said fulcrum bar at laterally spaced points, and a cutting jaw carried by each working lever, said fulcrum bar in that portion adjacent the cutting edges of said jaw having a wedge shaped section forming a deflector for the end of a wire when passed between said edges. 70

6. In a tool of the class described, a pair of operating levers pivotally connected to turn upon a common fulcrum, a pivot pin forming said fulcrum, a pair of spaced plates pivotally connected to each operating 80 lever and disposed on opposite sides of the same, a fulcrum bar disposed between said pairs of plates and extending across from the plates of one pair to those of the other with its side faces contiguous with the inner 85 faces of said plates, each pair of plates being separately pivoted to said bar at laterally spaced points intermediate the ends of the plates, the plates of each pair having flat parallel jaw receiving edges, each plate having in its inner surface a groove parallel to its jaw receiving edge and a portion of a screw thread the axis of which is disposed between said groove and edge and in parallel relation therewith, a jaw for each pair 90 of plates slidably mounted on said edges, a slide mounted between each pair of plates and having flanges engaged in said grooves, adjustable means connecting each jaw to its slide and adapted to draw the jaw against 100 said edges, and the flanges of said slide against certain of the walls of said grooves, and screws, one mounted in the threaded portions of each pair of plates to engage the outer end of the slide, said screws serving as 105 abutments to take the shocks imposed on the cutters.

In testimony whereof I have affixed my signature.

CHARLES P. FAY.
